UNITED STATES PATENT OFFICE

JAMES F. LOUCKS, OF CLEVELAND, OHIO, ASSIGNOR TO DETROIT STEEL PRODUCTS COMPANY, OF DETROIT, MICHIGAN, A CORPORATION OF MICHIGAN

BUILDING CONSTRUCTION

Application filed June 17, 1929. Serial No. 371,401.

This invention relates to building construction, and more particularly to the means for securing the wire-mesh backings and the wire ties employed with cement or plaster walls or partitions to structural beams or studs. It is the general purpose and object of the invention to provide simple and effective means for securing such backings and ties to such beams or studs.

10 The invention is particularly applicable to walls or partitions made up of bricks or tiles, united by cement or mortar and having a plaster face, wherein a wire-mesh backing is embedded in such plaster face and wire ties extend into the mortar between the bricks or tiles. By means of my invention, I am enabled to effect a quick and convenient fastening of the backing to the structural beams or studs associated with such 15 walls; also to anchor the wire ties to such beams or studs by the same fastening means which are employed to secure the backing thereto.

In the drawings forming part hereof, Fig. 25 1 represents a sectional view through a portion of a wall structure having my invention applied thereto; Fig. 2 a sectional view corresponding to the line 2—2 of Fig. 1 and looking in the direction of the arrows, the 30 fastening device and the tie being shown in elevation; Fig. 3 a detail in elevation corresponding to the line 3—3 of Fig. 1, the mortar or cement being omitted; Fig. 4 a detail in section corresponding to the line 35 4—4 of Fig. 2; Fig. 5 an elevation taken from one side of my fastening device; Fig. 6 a similar view taken from the opposite side; and Fig. 7 an elevation of the said device taken at right angles to Fig. 5.

40 Describing the various parts by reference characters, 1 denotes blocks, of brick or tile and laid up into a wall construction, the blocks being united by mortar or cement interposed therebetween, as shown at 2, and 45 having on one side thereof the plaster facing 3.

For convenience of description it will be assumed that the blocks are bricks arranged in horizontal courses and that the plaster 50 facing 3 extends vertically, as indicated in

Fig. 1. This plaster facing abuts against and partly covers one of the vertical flanges 4 on each of a plurality of angle beams, the other flange of each such beam being indicated at 5.

As a substitute for lath, a wire mesh backing is secured to the beams and is embedded in the plaster, an instance of such backing being that known to the trade as "Steeltex". This backing as shown herein consists of 60 suitably spaced wires 6 and 7 arranged at right angles to each other and adapted to be embedded in the plaster and mortar or cement when the wall is built up to the beams or studs. For the purpose of anchoring the backing and the wire ties I employ special fastening devices which cooperate with the backing and the ties as well as with the bolt openings 4^a and/or 5^a with which the beam flanges 4 and 5 are provided in a 65 manner to enable the backing and ties to be quickly and conveniently secured to the beams and to effect a firm anchorage for the said backing and ties.

Each of the fasteners referred to is made 75 of a continuous strip of soft flat steel bent to provide two opposed head members. One of these head members is shown as consisting of an upper portion 8 connected by a bend with a lower portion 9 from which 80 depends a shank member 10. The opposite head member consists of a loop 11 the outer leg 12 of which is bent downwardly and into engagement with a second shank member 10 adjacent thereto. The bottoms of 85 the shank members 10 are connected with upwardly extending tongue members 13, the members 13 projecting beyond the parts 8 and 11 and being connected therebeyond by an integral bend 14, the said members 13 90 jointly forming a tongue which, as stated, projects beyond the heads 8 and 11.

At a distance above the junction of each tongue member 13 with the bottom of its shank member 10, each such tongue member is provided with a weakened or bending line 15, each line being conveniently formed by removing some of the metal of such member, as by transversely grooving the same. The grooves 15 are arranged at such a dis- 100

- tance from the junction of each tongue member with its corresponding shank member that, when the tongue is driven inwardly into the plane of the head formed by the members 8 and 11, the grooves 15 will be in the plane of the bottoms of the members 10 and the parts of the tongue members 13 below such slots will extend horizontally outwardly, in the manner shown in Fig. 1.
- 10 In using my fastening or anchoring devices with the wire mesh backing and ties, I spring apart the legs comprising each a part 10 and an adjacent part 13 and insert therebetween one of the wires, as the wire 7. I also pass a wire tie 16 through the loop 11.
- 15 Each of the wire ties is constructed preferably in the manner shown in Fig. 2 and comprises a pair of legs each terminating in an outwardly directed foot 16^a, the tie being looped at the end opposite the said feet, as shown at 16^b. The ties having been secured to the backing in the manner described, the backing and ties are anchored 20 to the beams or studs as follows:—
- 25 The legs 10 and 13 and the lower end 12 of the loop 11 of each fastening device are inserted through the appropriate opening 4^a and/or 5^a, and the tongue 13, 14 is then driven through the said opening. The width 30 of the stock of the fastening device 8—15 is such that its edges will engage the inner wall of the opening 4^a and/or 5^a when the parts 13, 13^a are spread apart by the wire 7.
- 35 When the tongue 13, 14 and the head 8 and 11 have been driven in, the parts will assume the positions shown in Fig. 1; that is to say, when the grooves 15 have been brought to the bottom of the legs 10, the 40 top of the double tongue and the tops of the head members 8 and 11 will be substantially the same plane, the parts 8 and 11 being driven in somewhat to provide an effective head engaging one side of the flange 4 or 5. The driving action will cause the parts 13^a of the tongues below the slots 15 to extend horizontally outwardly, as shown in Fig. 1; and the binding of the edges 45 of the fastening device against the inner wall of the opening 4^a or 5^a will prevent the wire 7 from reaching the top of the space between the tongues 13, thereby bending such wire outwardly, as shown in Figs. 1 and 2, and holding the adjacent body portion 50 of the backing in close engagement with the flange 4 or 5. The eye or loop 11 is so arranged that the body of the wall tie may extend directly or horizontally outwardly from the loop or eye, thereby to be 55 embedded in the mortar or cement between the courses of brick or tile. When the fastening device shall have been driven home in the manner described, it will be anchored firmly to the beam flange by the engagement 60 of the head with one side of the flange 65

and the engagement of the inner ends of the convergent parts 10^a of the shank members 10—see Fig. 1. In other words by driving the tongue, the opposite end of the device is automatically upset and the device is anchored by the head on one side and the divergent parts 10^a on the other side.

70 For convenience of description it has been assumed that the beams 4, 5 are arranged in the particular manner shown in the drawings and that the wall or partition to be erected will be a vertical wall, with the courses of brick or tile arranged as shown. However, by such particularity of description, I do not preclude myself from protecting the use of my invention in connection with other arrangements of studs or beams and walls or partitions.

75 In practice, the wire ties are applied to the respective fastening devices and the latter are each driven or pressed over a wire of the backing, and the backing, together with the ties and fasteners, is applied to the structural beams or studs in the manner shown, after which the wall is built up and 80 the ties and backing are placed and embedded in the plaster, mortar, or cement in the manner shown.

85 Having thus described my invention, what I claim is:

90 1. A backing construction for walls or partitions comprising a wire mesh, and integral flat metal fastening devices for securing the said mesh to one or more structural beams, each of said devices consisting of a 95 pair of head members and a shank comprising a flat metal side member projecting from each head member, with a central tongue projecting upwardly between said side members and beyond said head, the tongue comprising a pair of members integrally connected with the bottoms of the shank members, each tongue member having a bending line above the bottom thereof so arranged that, when the shank is inserted 100 through an opening in a beam and the central projecting portion of the tongue is driven into substantially the plane of the head, the parts of the tongue members below said bending line assume a position substantially at right angles to the remaining 105 parts of the tongue members, each of the said devices receiving a wire of said backing between the members of the tongue of such device.

110 2. A backing construction for walls or partitions comprising a wire mesh, and integral fastening devices for securing the said mesh to one or more structural beams, each of said devices consisting of a pair of head members and a shank comprising a flat metal side member projecting from each head member, with a central tongue projecting upwardly between said side members and beyond said head, the tongue comprising 115

- ing a pair of members integrally connected with the bottoms of the shank members, each tongue member having a bending line above the bottom thereof so arranged that, when the shank is inserted through an opening in a beam and the central projecting portion of the tongue is driven into substantially the plane of the head, the parts of the tongue members below said bending line assume a position substantially at right angles to the remaining parts of the tongue members, each of the said devices receiving a wire of said backing between adjacent parts of such device.
5. Means for securing a wire tie for building walls or partitions to a structural beam, comprising an integral fastening device consisting of a pair of head members each having a flat metal shank member, with a central tongue comprising a pair of side members integrally connected with the bottoms of the shank members, each tongue member having a bending line above the bottom thereof so arranged that, when the shank members are inserted through an opening in a beam and the central projecting portion of the tongue is driven into substantially the plane of the head, the parts of the tongue members below said bending line assume a position substantially at right angles to the remaining parts of the tongue members, each fastener adapted to receive a portion of a tie between adjacent portions thereof. 70
10. 3. A backing construction for walls or partitions comprising a wire mesh and looped wire ties, and integral flat metal fastening devices for securing the said mesh and ties to the openings of structural beams, each fastening device comprising a head having a pair of head members one of which is provided with a loop receiving the loop of a wire tie, and each device having a shank comprising a flat metal side member projecting from each head member, with a flat metal central tongue projecting between said side members and beyond said head, the tongue comprising a pair of flat metal members integrally connected with the bottom of the shank members and each having a bending line above the bottom thereof so arranged that, when the central projecting portion of the tongue is driven into substantially the plane of the head, the parts 75
15. 34. of the tongue members below said bending line assume a position substantially at right angles to the remaining parts of the tongue members, each of the said devices receiving a wire of said backing between the central members of the tongue of such device.
20. 4. A backing construction for walls or partitions comprising a wire mesh and looped wire ties, and integral fastening devices for securing the said ties to the said mesh and the mesh to the openings of structural beams, each fastening device comprising a head having a pair of head members one of which is provided with a loop, and each device having a shank comprising a side member projecting from each head member, with a central tongue projecting between said side members and beyond said head, the tongue comprising a pair of members integrally connected with the bottoms 80
25. 55. of the shank members and each having a bending line above the bottom thereof so arranged that, when the central projecting portion of the tongue is driven into substantially the plane of the head, the parts of the tongue members below said bending line assume a position substantially at right angles to the remaining parts of the tongue members, each fastener adapted to receive a wire of the said backing between adjacent parts thereof. 85
30. 6. Means for anchoring a wire mesh backing for walls or partitions to structural beams, the said means comprising a plurality of integral fasteners each having a pair of head members and a shank member extending from each head member, with a central tongue projecting upwardly between said shank members and beyond said head, the tongue comprising a pair of side members integrally connected with the bottoms of the shank members, each tongue member having a bending line above the bottom thereof so arranged that, when the shank members are inserted through an opening in a beam and the central projecting portion of the tongue is driven into substantially the plane of the head, the parts of the tongue members below said bending line assume a position substantially at right angles to the remaining parts of the tongue members, each fastener adapted to receive a wire of the said backing between adjacent parts thereof. 90
35. 7. Means for anchoring to a structural beam a metallic backing for walls or partitions, the said means comprising an integral fastening device consisting of a length of metal bent upon itself to form a shank consisting of two externally arranged shank members at least one of said shank members having a head member at one end thereof, and a tongue comprising a pair of members interposed between the shank members and extending beyond the head member, the said fastening device adapted to receive between adjacent portions thereof a part of the said backing and to have the ends of the shank members thereof opposite the tongue automatically upset by driving the tongue toward the head member, whereby the said device may be inserted in an opening in such structural beam and automatically locked to opposite sides of such opening by driving the said tongue. 95
40. 8. Means for anchoring to a structural 100
45. 9. 110
50. 10. 115
55. 11. 120
60. 12. 125
65. 13. 130

- beam a backing for walls or partitions, the said means comprising an integral fastening device adapted to be applied to a part of the said backing and comprising a head member adapted to engage a portion of the backing, a shank member extending from said head member and a tongue member extending from the shank member and projecting beyond the head member, the tongue member being provided with a bending line intermediate its ends whereby, on driving such projecting end thereof into substantially the plane of the head member, the portion of the tongue member beyond the bending line will assume a position at an angle with respect to the other portion of the tongue member, thereby projecting a portion of the shank member into engagement with the said beam.
9. Means for anchoring to a structural beam a metallic backing and a wire tie for walls or partitions, the said means comprising an integral fastening device adapted to be applied to a part of the said backing and to such tie and comprising a head adapted to engage one side of an aperture in such beam, said head having a loop adapted to receive a portion of the metallic backing, a shank extending from and beyond said head, a tongue connected at one end to the end of said shank and having a looped end extending beyond said head, the said tongue being provided with a bending line intermediate the ends thereof, the loop in said tongue receiving the tie and the parts being arranged so that when the looped end of the tongue is driven into substantially the plane of the head, the portion of the tongue beyond the bending line will assume a position forming an angle with respect to the other portion of the tongue, thereby projecting a portion of the shank member into engagement with the said beam.

In testimony whereof, I hereunto affix my
signature.

JAMES F. LOUCKS.
